UNITED STATES PATENT OFFICE

173,036

WRENCH

George Y. Morton, San Francisco, Calif.

Application March 11, 1954, Serial No. 29,469

Term of patent 14 years

(Cl. D54—16)

To all whom it may concern:

Be it known that I, George Y. Morton, of the city and county of San Francisco, State of California, have invented a new, original, and ornamental Design for a Wrench, of which the following is a specification, reference being had to the accompanying drawing, forming a part hereof.

Fig. 1 is a perspective view of a wrench, showing my new design.

Fig. 2 is a front elevation, and

Fig. 3 is a side elevation.

I claim:

The ornamental design for a wrench, as shown.
